UNITED STATES PATENT OFFICE.

FRANK W. WHITE, OF BROOKLYN, NEW YORK.

ATTACHMENT FOR TOOLS.

1,106,264.

Specification of Letters Patent.

Patented Aug. 4, 1914.

Application filed June 12, 1912. Serial No. 703,351.

To all whom it may concern:

Be it known that I, FRANK W. WHITE, a citizen of the United States, residing at Brooklyn, in the county of Kings and State 5 of New York, have invented new and useful Improvements in Attachments for Tools, of which the following is a specification.

The present invention relates to a holding attachment for rivet sets, chisels or similar tools employed in connection with pneumatic or electric hammers, and resides in the construction, combination and arrangement of parts set forth in the following specification and falling within the scope of 15 the appended claim.

In the drawing, Figure 1 is a side elevation of my improvement in applied position. Fig. 2 is a top plan view of the improvement detached, parts being shown in 20 section.

It is well known to those familiar with the operation of pneumatic or electric hammers that the trigger for operating the same is extremely sensitive and that when the hammer is temporarily withdrawn from its work and laid aside, a jolt or jar of the scaffold upon which the said hammer is supported will accidentally operate the trigger and cause the rivet set or chisel to be projected 25 therefrom at a great velocity. The trigger is also liable to actuation by a work-man accidentally contacting the same with his foot or hand, by tools or timbers being carelessly thrown upon the scaffold or other support upon which the hammer has been temporarily laid and which contact with the trigger of the hammer, and from other innumerable causes which will accidentally 30 actuate the piston of the hammer.

In the drawing, the numeral 1 designates 40 an ordinary pneumatic hammer, having the operating trigger 2 and being provided with a suitable tool 3, such as a rivet set. The handle 4 of the hammer is of the conventional U-shaped construction, and as the working parts of the hammer do not form any part of the present invention, the same 45 will not be referred to in detail.

The numeral 5 designates my improved 50 tool holding device in its entirety. The device contemplates the employment of a split ring 6, which is adapted to be arranged upon the tool 3 and to contact with its flange or head or that portion of the said tool opposite its shank, the latter being received

within the hammer proper. Pivottally connected as at 7 between the offset ends of the split ring 6 is a rod 8 which has one of its ends provided with a head 9. This head 9 is adapted to be received within a cylinder 60 10, the said cylinder having one of its ends open and threaded. The numeral 11 designates a cap for the said threaded end of the cylinder. This cap is provided with a threaded bore 12, and the said cap is further provided with a reduced extending finger 13. Pivottally connected as at 14 with the finger 13 are the offset ends 15 provided by a substantially split U-shaped member 16, and this member is adapted to be positioned upon the handle 4 of the hammer opposite that portion thereof upon which is arranged the trigger 2. Surrounding the rod 8 and exerting a pressure between its head 9 and the closed end of the cylinder 10 70 75 is a helical spring 17, the latter being provided in order to compensate for the shock or jar incident to the operation of the piston of the hammer when the trigger 2 has been accidentally contacted and also to permit of 80 the tool 3 being ejected from the hammer a slight distance, the said distance however, not being sufficient to permit of the shank of the tool leaving the bore of the hammer.

Either or both of the pivots 7 and 14 may 85 be removable, and it will thus be noted that the device may be easily and quickly positioned upon the hammer, and from the above description, taken in connection with the accompanying drawing, the simplicity of the 90 device as well as the advantages thereof will commend themselves, it is thought, to those skilled in the art to which such inventions appertain without further detailed description.

While the device has been described and illustrated as connected with the handle of the hammer, it is, to be understood that the same may be connected with equal efficiency to the barrel of the said hammer.

Having thus described the invention, what I claim is:—

In combination with an ordinary pneumatic hammer provided with the usual handle and provided with a flanged tool which is operated by the hammer, of means for preventing the accidental removal of the tool from the barrel of the hammer, said means including a substantially ring-shaped member which is adapted to be arranged 105 110 115

upon the handle, a cylinder connected with the ring-shaped member, a rod having a head arranged within the cylinder, a spring between the outer face of the cylinder and the head of the rod, and a split ring connected to the free extremity of the rod and adapted to encircle the tool.

In testimony whereof I affix my signature in presence of two witnesses.

FRANK W. WHITE.
